CLAIM

The ornamental design for a UV sterilization light, as shown and described.

DESCRIPTION

FIG. 1 is a front, top perspective view of a UV sterilization light showing my new design;

FIG. 2 is a rear, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view of the UV sterilization light shown in an alternate configuration of use; and,

FIG. 10 is a rear perspective view thereof.
